UNITED STATES PATENT OFFICE.

ROY CUSICK, OF CARNEGIE, PENNSYLVANIA.

VENDING MACHINE.

Application filed May 20, 1919. Serial No. 298,505.

To all whom it may concern:

Be it known that I, ROY CUSICK, a citizen of the United States, residing at Carnegie, in the county of Allegheny and State of Pennsylvania, have invented new and useful Improvements in Vending Machines, of which the following is a specification.

This invention comprehends the provision of a vending machine, primarily intended 10 to vend pencils, although it is susceptible for use to vend other merchandise, one of the objects residing in the provision of a novel construction, of a coin controlled mechanism to regulate the discharge of the merchandise 15 from the machine.

The invention has other objects in view which will appear as the nature and advantages of the invention are better understood 20 from the following detailed description taken in connection with the accompanying drawing, the invention residing in the construction, combination and arrangement of parts as claimed.

In the drawings forming part of this 25 specification, like numerals of reference indicate similar parts in the several views, and wherein:—

Figure 1 is a perspective view of a machine constructed in accordance with my invention.

Figure 2 is a vertical central sectional view taken therethrough.

Figure 3 is a horizontal sectional view taken on line 3—3 of Figure 1.

Figure 4 is a detail view of the roller.

Figure 5 is a side elevation with certain of the side plates removed showing the normal position of the coin actuating element.

Figure 6 is a similar view showing the coin controlled mechanism and the normal position of parts.

Figure 7 is a vertical sectional view taken on line 7—7 of Figure 6.

Figure 8 is a detail view of the hopper and its associated parts.

Figure 9 is a detail view of the coin controlled sliding plates.

A machine constructed in accordance with my invention eventually embodies a receptacle including side walls 10, bottom 11,

front and rear walls 12 and 13 respectively, and a hingedly mounted top 14. The top 14 may be locked to the rear wall 12 as at 15, by any suitable mechanism. It might here be stated that the receptacle may vary in size and configuration, and may be constructed from any suitable material without departing from the spirit of the invention. The side walls 10 are provided with bearings for the opposite ends of a shaft 16 which extends thru the roller 17, the latter being arranged within the receptacle for rotation. As the machine is primarily intended to vend pencils, or other articles having an analogous configuration or substantially so, the roller 17 is provided with a longitudinally extending groove 18 which is normally disposed to receive an article of merchandise and discharge the same from the receptacle in a manner to be hereinafter described. It is manifest, that the roller 17 may be designed, or provided with means to accommodate different articles of merchandise, thus rendering the machine susceptible for an unlimited number of uses.

Arranged within the receptacle is what I term a hopper, including a front wall 19, and a rear wall 20 which is inclined from an appropriate point in its height in the direction of the rear wall 13 of the receptacle with which it contacts. The front and rear walls 19 and 20 respectively are connected by the side walls 21, and the latter are suitably secured to the corresponding walls of the receptacle. Projecting forwardly from a point adjacent the lower end of the hopper, are spaced parallel shelves 22 and 23 respectively, each of which has its opposite sides suitably secured to the side walls of the receptacle. As shown in Figure 8, the roller 17 is arranged to rotate between the shelves 23 and 22, the former having a curved extension 24 partly overlying the roller 17, and utilized to maintain the article of merchandise positioned within the groove 18 as the roller is being rotated in a direction to discharge the article from the machine. It is to be understood that the space between the front and rear walls 19 and 20 respectively of the hopper adjacent the roller 17 is restricted so that

the pencils or other articles of merchandise arranged within the hopper will be singly fed to the groove 18 of the roller.

As hereinabove stated, the roller 17 normally occupies a position with the groove 18 arranged within the hopper, a coiled spring 25 encircling the shaft 16 of the roller, and having one end fixed to said shaft and its opposite end to the adjacent wall of the receptacle, the spring being utilized to maintain the roller in the position stated.

A pair of substantially rectangular plates 26 and 27 respectively are disposed in juxtaposition, and are connected together and with one of the side walls 10 of the receptacle by means of bolts or suitable fastening elements 28. The plates 26 and 27 are provided with alined openings 29 for the reception of one end of a shaft 16, and these plates are further provided with alined elongated slots 30 for a purpose to be hereinafter set forth. A substantially triangular shaped spacing element 31 is arranged between the plates 26 and 27 at one corner thereof, the element 31 serving to hold said plates slightly spaced apart. Embracing the shaft 16 is a collar 32 provided with an inwardly disposed lug 33 which is positioned within a groove 34 in the shaft, so that the collar is fixed upon the shaft for rotation therewith. Projecting rearwardly from the collar 32 is an extension 35 which acts against the coin to effect an operation of the coin controlled mechanism in the manner to be hereinafter described. The coin actuated element is illustrated in Figure 9, and includes an elongated body portion 36 arranged upon the outer side of the plate 27 for sliding movement transversely thereof. Guide pins 37 project from the plate 27 at opposite sides of the element 36, to guide the latter in its adjustment. Projecting from the sides of the body portion 36 are studs 38 arranged to slide in the alined slots 30 of the respective plates 26 and 27. The body portion 36 is provided with a slot 39 in which one end of a spring 40 is arranged, the opposite end of the spring being secured to a pin 41 carried by the plate 27. The spring 40 is utilized to normally maintain the coin controlled element in a position where the lug 42 projecting from one end thereof, engages the disk 43, which is fixed upon the shaft 16 for rotation therewith. The disk is cut away as at 44 to provide the shoulders 45 and 46 respectively, which latter cooperate with the lug 42 to limit the rotation of the shaft 16 in opposite directions. A plate 47 having a configuration 5 similar to the plates 26 and 27 respectively is arranged in juxtaposition to the plate 27 and secured thereto by means of the bolts 28. Manifestly, the plate 47 is employed to close the coin controlled mechanism, and is provided with an opening 65 for the reception of the adjacent end of the

shaft 16. This opening 48 is relatively large and shaped to provide opposed shoulders 48' adapted to be alternately engaged by the lug 49 on one end of a crank handle 50, to limit the movement of the handle. The side walls 10 of the receptacle, and parallel plates 26, 27 and 47 are cut away as at 51 for the reception of the coin receiving box 52 which is arranged to slide across the bottom 11 of the receptacle. Any suitable locking means indicated at 53 may be employed for locking the box 52 in the receptacle.

In practice, the coin of proper denomination is inserted within the coin slot 54, entering the space between the plates 26 and 27 respectively. The handle 50 is then actuated to rotate the shaft 16, and as the collar 32 is fixed upon this shaft for rotation therewith, the extension 35 forces the coin from the position it occupies in Figure 5 beneath the stud 38 from where it has an unobstructed passage to the coin receiving box 52. However, during the movement of the coin, under the influence of the extension 35, the element 36 is moved in a direction away from the disk 43, and against the tension of the spring 40. In this position of the element 36, the shaft 16 may be further rotated through the instrumentality of the handle 50, to a position where the article of merchandise will gravitate from the groove 18 of the roller upon the shelf 23. The shelf 23 is arranged in a horizontal alinement with a slot 55 in the front wall 12 of the receptacle, thru which slot the article of merchandise is discharged from the machine. Subsequent to the release of the handle 50, the spring 25 functions to return the roller 17 to its normal position, whereupon another article of merchandise is positioned within the groove 18. It is of course manifest, that after the coin has been displaced from its initial position by means of the extension 35, the spring 40 functions to return the element 36 to its normal position in engagement with the disk 43.

I have shown and described what I consider the preferred embodiment of the invention, and I desire to have it understood that I do not limit myself in this respect, as such changes may be resorted to when desired as fall within the scope of what is claimed.

What I claim is:—

The combination of a casing, a pair of spaced parallel plates mounted at one side of the casing forming a coin chute, a shaft rotatably mounted in the casing and having one end journaled thru said plates, a collar mounted on the shaft for rotation therewith between said plates, a disk provided with a recess mounted on the shaft, a coin controlled element slidably mounted upon the outer side of one of said plates and

having one end normally disposed within said recess in the disk to prevent rotation of the shaft, a projection on the coin controlled element adapted to engage a coin at one side, 5 an extension on the collar adapted to engage said coin at its opposite side, said projection and extension forming a retaining means for a coin placed in the chute, and means to

rotate said shaft whereby said extension rotatably carried thereon will force the coin 10 against the opposite projection sliding the coin controlled element from engagement with the recess in the disk.

In testimony whereof I affix my signature.

ROY CUSICK.
